UNITED STATES PATENT OFFICE.

CHARLES W. BECK, OF ROCKVILLE CENTER, NEW YORK, ASSIGNEE, BY MESNE ASSIGNMENTS, TO MICHIGAN MOTOR SPECIALTIES COMPANY, OF DETROIT, MICHIGAN, A CORPORATION OF MICHIGAN.

TERMINAL CONNECTOR FOR SPARK-PLUGS.

1,108,674.

Specification of Letters Patent.

Patented Aug. 25, 1914.

Application filed August 15, 1910. Serial No. 577,323.

To all whom it may concern:

Be it known that I, CHARLES W. BECK, a citizen of the United States, and resident of Rockville Center, county of Nassau, and State of New York, have invented certain new and useful Improvements in Terminal Connectors for Spark-Plugs, of which the following is a complete specification, reference being had thereto to the accompanying drawings, in which—

Figure 1 is a side elevation of a portion of a spark plug and a portion of a battery showing my improved terminal connector attached both to the spark plug and battery terminals; Fig. 2, a longitudinal sectional view of the connector adapted to engage the spark plug; Fig. 3 an elevation of the connector, the bridging piece and outer insulating sleeve being removed; Fig. 4 a longitudinal sectional view of the connector adapted to be attached to the binding post or other terminal of a battery; and Fig. 5 a transverse sectional view on the line V—V of Fig. 2.

In the use of the ordinary spark plug connecting means it is extremely difficult to determine whether or not the plug is sparking properly. It is a common practice to disconnect one terminal wire from the plug and hold the end thereof close to the other terminal wire, or to the other portion of the plug, one attendant holding the wire and the other cranking the engine when testing the plug.

The main object of this invention is to provide a terminal connector of simple form by means of which it may be readily determined whether or not any particular plug is sparking, and to so construct such terminal that it will serve as a lock to securely hold the terminal device connected to the spark plug, or to a battery terminal, and further to inclose the connector within an insulating protecting sleeve.

A further object of the invention is to so construct the device that all of the operating parts will be inclosed within a sleeve and protected thereby, whereby the device will be very neat in appearance and it will be practically impossible to break or damage the parts of the connector.

Another object of the invention is to provide means whereby a rigid sleeve carried

by the connector will serve to engage the spark plug or battery terminal and lock the connector thereto.

Another object of the invention is to provide means whereby any cylinder of a multiple cylinder explosive engine may be cut out or rendered inoperative by interrupting the sparking circuit.

The foregoing objects of the invention are mentioned merely by way of illustrating the general objects to be attained by the invention.

There are other important features of the invention which will be fully hereinafter described.

Referring to the various parts by numerals 1 designates the spark plug, which may be of any suitable construction formed with the usual post terminal 2. It will of course be understood that this post terminal may be of any desired form.

3 designates a battery terminal which may be a binding post of any suitable form.

The terminal connector for electrically connecting the terminal wire 4 to the spark plug consists of a central insulating block or base 5. This block is shown in the drawings as cylindrical but it will, of course, be understood that it may be of any desired shape in cross section. Rigidly connected to the outer end of this insulating base is a terminal hook 6 formed with the externally threaded socket 7 within which the end of the insulating base is rigidly secured, said socket forming one electrode of the connector. Rigidly secured to the other end of the insulating base is a conductor or electrode 8. This conductor is in the form of a long tube or socket which is adapted at its outer end to receive the inner end of the insulating base, said base being rigidly secured in said socket. Said socket is split longitudinally at its inner end to render it expansible; and it is provided with the inwardly extending lugs 9 near its inner end. The outer end of this socket is formed with a sparking point 10 which extends toward the socket 7 of the terminal hook, a spark-gap being formed between said sparking point and the inner edge of said socket.

The terminal wire 4 is provided on its end with a plug 11 which is adapted to enter the split portion of the socket 8, said plug

- being provided with an annular groove 12 in which the lugs 9 are adapted to fit and lock said plug within the socket. The conductor wire extends longitudinally through the plug and is rigidly and permanently locked thereto by means of solder 13 which is poured into a recess 14 formed in the end of the plug, shown clearly in Fig. 2. The plug is formed with an enlarged inner end 15 which is adapted to receive a portion of the insulation of the terminal wire and to form the shoulder 16 adapted to contact with the inner edge of the socket, shown clearly in Fig. 2.
- 10 To bridge the space or gap between the socket 7 and the socket 8, I provide a sleeve 17 which is internally threaded for a portion of this length to adapt it to be engaged with the external threads of the socket 7.
- 15 When said sleeve is so engaged it forms a means for bridging the gap between the two sockets and to electrically connect them together. The two sockets form two separated electrodes of the connector, and the 20 sleeve 17 forms a bridging piece or switch for connecting said two electrodes together electrically, whereby the electric current may readily flow from one electrode to the other, and to the terminal of the spark plug.
- 25 By unscrewing the sleeve until it is detached from the electrode 7 of the connector hook, the two members of the connector will be electrically disconnected and insulated from each other, and a spark will jump across 30 the gap between the sparking point 10 and the inner edge of the electrode 7. By this means it may be readily determined whether the spark plug is sparking properly. The shoulder 16 forms a stop for the inner end 35 of the sleeve 17 said shoulder being so placed and the bridging sleeve 17 being so proportioned that ample room will be provided to permit this disconnection of said sleeve from the socket 7 and the inward movement of 40 the sleeve to uncover the space between the two sockets or electrodes of the connector. Secured to the bridging sleeve 17 is an outer 45 sleeve 18. This outer sleeve is preferably of insulating material so that it may be readily grasped at any time for the purpose 50 of turning the sleeve 17 either for connecting the terminal with or disconnecting it from a spark plug. This insulating sleeve protects the sleeve 17 and all of the other 55 parts of the connector, and at the same time gives a smooth pleasing and durable finish to the device. The bridging sleeve 17 is of such length that it may be screwed forwardly or outwardly on the socket 7 to 60 bring the forward or outer edge thereof in contact with the spark plug terminal button or binding post, as indicated in Fig. 1 and in dotted lines in Fig. 2 to not only lock the terminal to the spark plug but to 65 assist in making a complete and satisfactory
- electrical connection between the terminal wire and the spark plug. It will therefore be seen that I provide a terminal connector of simple construction by means of which it may be readily ascertained whether or not the plug is sparking properly. The insulating and protecting sleeve 18 is of special advantage for the reason that it protects the operator from electric shocks which are very disagreeable.
- 75 To electrically connect the terminal wire to a battery terminal or binding post I secure a hook 19 to the terminal wire and form said hook with an external threaded socket 20 similar to socket 7 of the hook 6. On this socket is threaded a locking sleeve 21 whose outer end 21^a is adapted to contact with the battery binding post or terminal, as shown clearly in Fig. 1, and in dotted lines in Fig. 4, to lock the hook to said terminal post. It is manifest that the hook cannot be disengaged from the post without first withdrawing the locking sleeve.
- 80 Whenever it is desired to cut out a cylinder or render a cylinder inoperative by interrupting the sparking circuit, the terminal wire with its attached plug may be disconnected from the socket 8 by a sharp outward longitudinal pull on said wire. It is manifest that it may be readily connected to the 85 socket by forcing it therein until the lugs 9 snap into the groove 12 and thereby restore the connection. The two sockets 7 and 8 form two contact plates or electrodes which are secured to the insulating base 5, and 90 are separated from each other a sufficient distance to prevent the jumping of the electric current across said space except at the point 10. It is manifest that the sleeve 17 forms a bridge or switch for electrically 95 connecting the two contact plates or electrodes so that electric current may readily flow from the terminal wire to the spark plug. By unscrewing the bridging sleeve it may be withdrawn to expose the sparking 100 point so that it may be observed whether or not the plug is sparking properly.
- 105 Having now fully described my invention what I claim as new, and desire to secure by Letters Patent is:
- 110 1. In a terminal connector the combination with an insulating base; fixed electrodes mounted on said base and having a space between them, a movable sleeve adapted to inclose said electrodes and to bridge the 115 space between them, whereby said electrodes may be electrically connected together by said sleeve, and means for electrically connecting one of said electrodes to a spark plug terminal and means for connecting the other electrode to a terminal wire.
- 120 2. In a terminal connector the combination with an insulating base; fixed electrodes mounted on said base and having a space between them, movable means for inclosing 125
- 130

5 said electrodes and bridging the space between them, said means serving to electrically connect said electrodes together, means for connecting one of said electrodes to a spark plug terminal, and means to connect the other electrode to a terminal wire.

10 6. In a terminal connector the combination with an insulating base, fixed electrodes mounted on said base and having a space between them one of said electrodes being externally threaded, an internally threaded sleeve adapted to engage the threaded electrode and to bridge the space between said electrodes, means for connecting one of said electrodes to a spark plug terminal, and means for connecting the other electrode to a terminal wire.

15 7. In a terminal connector the combination with an insulating block or base, electrodes mounted on said base and having a space between them one of said electrodes having a projecting-sparking point extending toward the other electrode, and tubular movable means for bridging the space between the electrodes and inclosing the sparking point, said means being adapted to open and close the circuit between said electrodes.

20 8. In a terminal connector the combination with an insulating base, fixed electrodes mounted on said base and having a space between them one of said electrodes being adapted to be connected to a spark plug terminal, means for connecting the other electrode to a terminal wire, and a longitudinally movable sleeve for bridging the gap between said electrodes said sleeve in its bridging position being adapted to contact with the spark plug terminal to lock the electrode thereto.

25 9. In a terminal connector the combination with an insulating base, electrodes mounted on said base and having a space between them, a longitudinally movable sleeve for electrically bridging said space and thereby closing the circuit between said electrodes.

30 10. In a terminal connector the combination with an insulating base, electrodes mounted on said base and having a space between them one of said electrodes having a projecting sparking point extending toward the other electrode whereby a spark across the space will take place at said extended point, a longitudinally movable sleeve for bridging said space between the electrodes and closing the circuit between them.

35 11. In a terminal connector the combination with an insulating base, two electrodes connected thereto and spaced apart, one of said electrodes being provided with means for connecting it to a spark plug terminal the other being formed with a socket, a terminal wire, a plug connected to said wire and adapted to fit the electrode socket, one of said electrodes being externally threaded,

40 an internally threaded bridging sleeve adapted to engage the threaded electrode and to bridge the space between the two electrodes, said sleeve being adapted in its bridging position to contact with the spark plug terminal to lock the electrode thereto.

45 12. In a terminal connector the combination of an insulating base, fixed electrodes mounted on said base and having a space between them one of said electrodes being externally threaded, a socket formed on one of said electrodes, an internally threaded bridging sleeve adapted to engage the threaded electrode and to bridge the space between the electrodes, a terminal wire, a plug connected to said wire and adapted to fit the electrode socket, and an insulating and protecting sleeve carried by the bridging sleeve.

50 13. In a terminal connector the combination with an insulating base, fixed electrodes mounted on said base and having a space between them, movable means for inclosing said electrodes and bridging the space between them, said means serving to electrically connect said electrodes together, means for connecting one of said electrodes to a spark plug terminal, means to connect the other electrode to a terminal wire, and an operating sleeve of insulating material connected to said movable means and inclosing and protecting the means for connecting the electrodes to the terminal wire.

55 14. In a terminal connector, the combination with an insulating base, electrodes mounted on said base and having a spark gap between them, a longitudinally movable sleeve for electrically bridging said space and thereby closing the circuit between said electrodes, a terminal wire, means for detachably connecting the wire to one of the electrodes and an operating sleeve of insulating material carried by the movable sleeve and inclosing the connection between the wire and the electrodes.

60 15. In a terminal connector, the combination with an insulating base, electrodes mounted on said base and having a space between them, one of said electrodes being adapted to be connected to a spark plug terminal, a longitudinally movable sleeve for electrically bridging the space between the electrodes and adapted to be brought into contact with the spark plug terminal, thereby closing the circuit between the electrodes and locking one of the electrodes to the spark plug terminal.

65 16. In a terminal connector, the combination with an insulating base, electrodes mounted on said base and having a space between them, one of said electrodes being provided with means for engaging a spark plug terminal, and a longitudinally movable locking sleeve for electrically bridging the space between said electrodes and adapted

to move outwardly over the means for engaging the spark plug terminal to lock said means to the terminal.

14. A terminal connector comprising a contact part adapted to be connected to a spark plug terminal, a contact part adapted to be connected to a terminal wire, a rotatable operating sleeve of insulating material inclosing said contact parts and means whereby the rotation of said sleeve in one direction will open a spark gap between the contact parts and whereby its rotation in the opposite direction will close said gap between said parts.
15. A terminal connector comprising a contact part adapted to be connected to a spark plug terminal, a contact part adapted to be connected to a terminal wire, means for supporting said contact parts with a spark gap between them, a sleeve of insulat-

ing material inclosing said contact parts and rotatable means for opening and closing the spark gap between said contact parts.

16. A terminal connector comprising a contact part adapted to be connected to a spark plug terminal, a contact part adapted to be connected to a terminal wire, insulating means between and supporting said contact parts, a rotating device of insulating material and means whereby upon the rotation of said device, the spark gap between the contact parts may be opened or closed.

In testimony whereof I hereunto affix my signature in the presence of two witnesses this 4th day of August, 1910.
